(57) **CLAIM**

The ornamental design for a casing with wallet for electronic device, as shown and described.

DESCRIPTION

FIG. 1 is a front right perspective view of a casing with wallet for electronic device showing my new design;

FIG. 2 is a front left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front right perspective view thereof, shown in an open position;

FIG. 10 is a rear perspective view thereof, shown in an open position; and,

FIG. 11 is a reduced front left perspective view thereof, illustrating the casing with wallet for electronic device in use with a neck lanyard.

The broken lines in the drawings represent unclaimed environmental subject matter that forms no part of the claimed design.
